UNITED STATES PATENT OFFICE.

THAXTER SHAW, OF VANCEBOROUGH, MAINE.

LEATHER-DRESSING MACHINE.

SPECIFICATION forming part of Letters Patent No. 449,707, dated April 7, 1891.

Application filed April 1, 1889. Serial No. 305,608. (No model.)

To all whom it may concern:

Be it known that I, THAXTER SHAW, a citizen of the United States, residing at Vanceborough, in the county of Washington and State of Maine, have invented a new and useful Machine for Reducing Spots on Hides in the Process of Tanning; and I do hereby declare that the following is a full, clear, and exact description of the invention, which will enable others skilled in the art to which it appertains to make and use the same.

My invention relates to a machine for reducing spots on hides in the process of tanning, and is illustrated in the accompanying drawings in two sheets, in which—

15 Figure 1 represents a side elevation of my machine as set up ready for use. Fig. 2 represents a front elevation of the drum of my device with its supports. Fig. 3 is a side view 20 of the manner of constructing the upper part of my device and attaching the same to a wall. Fig. 4 is a front view of the construction shown in Fig. 3. Fig. 5 is a plan view of the entire machine as constructed and set up 25 in Fig. 1. Fig. 6 is a plan of the head or upper part of my machine as constructed when the main shaft and driving-pulley are situated nearer the wall than is shown in the other figures. Fig. 7 is a side view of the construction shown in Fig. 6.

Similar letters of reference refer to correspondingly like parts through the different figures.

In the process of tanning after the hides 35 have been unhaired and cleaned they are placed in tan-pits filled with tannin-liquor and steeped by being successively handled or transferred from vats containing a weak solution to those of a stronger mixture. During 40 this process of handling there invariably appears upon the grain side of the hides more or less white and yellow spots, which if allowed to remain grow more distinct as the process continues and spoil the leather for the market. These spots have a greasy appearance 45 and cannot be penetrated by the tannin-liquor until removed or raised, which latter process has previously been done either by acids applied to the spots or by rubbing the same by hand with a gritty substance, such as pieces 50 of grindstone or brick. The objections to

these two methods are that the former impairs the strength of the leather, while the latter is necessarily slow, tedious, and thus expensive, and it is to overcome these objections and 55 produce a machine that will quickly and effectively reduce the said spots without injury to the hides that I have invented my device, which consists of a drum or cylinder mounted upon standards in such manner as 60 to allow both a revolving and lateral motion, and a suspended swinging apparatus carrying a rapidly-revolving wheel composed of a fine gritty substance located above the drum and adapted to be operated upon its surface, as 65 will now be described.

In the drawings, A represents a drum or cylinder with closed ends, constructed of a sufficient size for the purpose desired and containing a shaft B extending longitudinally 70 through its center and projecting some distance beyond its ends. This shaft B may be confined to the drum A in any usual manner, and I have shown it with face-plates a rigidly fastened to the shaft and then bolted to each 75 end of the drum. The drum A is held horizontally a sufficient height above the floor by having the projecting ends of the shaft B rest upon grooved wheels D, which in turn are adapted to travel upon short tracks l, 80 confined to upright supports C, placed each side of the shaft and firmly bolted to the floor, as shown in Figs. 1, 2, and 5. By this arrangement the drum A can be easily revolved by hand as the nature of the work requires, and 85 also moved longitudinally toward either support.

The supports C, I preferably construct of iron rods, by leaving a short distance in the center for the track l, bending the rod upward at each end of the track and doubling or making a return-bend of these upward portions at a short distance above the track l, and finishing the ends in a manner to be attached to the floor. The short projections at 95 each end of the track l above the same serve to prevent the axes of the grooved wheels D from running beyond the ends of the track.

Fastened to the wall in such position that it will swing and operate over the surface of 100 the drum A is an attachment carrying the scouring or raising wheel, constructed as fol-

lows: Using the construction shown in Figs. 1 and 5, two short strips of wood H H are fastened to the wall I by having their ends secured by bolts or other means to a cleat or beam located a sufficient height upon the said wall. The projecting ends of the strips H are connected by the cross-piece i, from which depends two arm-supports G G, supported and rigidly held by braces T, connected thereto and fastened to the wall I. The depending ends of the arm-supports G are provided with lateral holes bored therein, through which a circular rod e is inserted. This rod e has attached thereon and depending therefrom the two arms F F, which are of sufficient length to extend down to and over the top of the drum A. The lower ends of the arms F are connected by a cross-piece u, (shown in Fig. 5,) from which projects a handle h of sufficient length to accommodate the operator. Just above the cross-piece u is a shaft carrying a grinding-wheel E and provided with a belt-pulley t. This shaft is confined to the arms F by boxes thereon, connected in the usual way, and the said shaft is revolved by means of a belt b, passing around the pulley t and over the driving-pulley W of larger diameter, situated between the arm-supports G G and confined to a main or counter shaft J. The driving-pulley W should be made with a broad surface, in order to allow for a slight lateral movement of the arms F F of the frame. This lateral movement may be attained in several different ways.

In Figs. 1, 5, 6, and 7, the arms F F are attached to the cross-rod e between the arm-supports in such a manner as to allow a slight lateral play by means of the cross-rod e sliding through the holes bored in the said supports.

In Figs. 3 and 4 the wall-strips H H are attached to the wall at an acute angle, and the cross-bar i connecting their outer ends is mortised into the said wall-strips, and its upper surface rises flush with the latter. Braces T support and add stability to the said wall-strips H. The arm-supports G G are constructed the same as hereinbefore described with the addition of a cross-bar k, connecting their upper ends opposite those to which the arms F F are attached. The arm-supports G G are pivoted to the wall-pieces H by the use of a bolt o, passing through the center of their respective cross-bars i and k, this construction allowing the desired side movement. The grinding-wheel E is prevented from touching the surface of the drum A when not in use by means of a spring of any desired form suspended above and connected to the lower part of the arms F.

The manner of using my machine is as follows: A spotted hide is laid upon the drum A, grain-side up, and the drum moved by hand until the spot to be treated is brought under the rapidly-revolving grinding-wheel E. The operator, by the use of the handle h, brings the grinding-wheel to bear upon the

grease-spot, and by the slight lateral movement of the arms F, combined with the different motions of the drum A, grinds or raises 70 the entire surface of the grease-spot sufficiently to obliterate the latter. All spots upon a hide can thus be effectively treated in a very few moments, and when raised and placed in the vats will receive the tannin and 75 color the same as the rest of the hide.

Having thus described my invention and the manner in which it is used, what I claim, and desire to secure by Letters Patent of the United States, is—

1. In a machine for the purpose described, the drum A, the shaft B, projecting longitudinally from each end thereof, the standards C, attached to the floor in pairs near each end of the drum and provided with short tracks l at their upper portions, the rollers D, having their axes traveling on the said tracks l and their periphery grooved to receive the shaft B, in combination with a revolving grinding-wheel connected to a suitable power medium 85 and attached to a vertically-moving hinged frame or arms F F in such manner as to be supported over said drum and adapted to be brought in contact with the surface of the latter at the will of the operator, substantially 90 as shown and described.

2. In a machine for the purpose described, the grinding apparatus consisting of the strips H, projecting from the wall, the arm-supports G, attached to the strips H and supported by braces T or other means, the driving-pulley W, located between the arm-supports and attached to a main or counter shaft connected with a suitable power medium, the swinging arms F, hinged to the 105 arm-supports depending therefrom and containing the operating-handle h at their lower ends with the grinding-wheel E and its shaft confined to the arms F and operated by a belt passing over the driving-pulley W, in 110 combination with a cylindrical drum A, having protruding longitudinal axes mounted upon suitable supports in such manner as to allow both a revolving and longitudinal movement, all substantially as shown, and for the 115 purpose set forth and described.

3. A machine for reducing spots on hides, consisting of the combination of the grinding apparatus composed of the wall-strips H, arm-supports G, swinging arms F with 120 operating-handle and suspending-spring, grinding-wheel E with its shaft and pulley, driving-pulley W, located between the arm-supports, for the purpose described, with the drum A, having the extending shaft B, 125 supports C, with tracks l at their upper portions, and grooved wheels D, traveling on said tracks and supporting the drum-shaft B each side of the drum, substantially as shown and described.

4. A machine for the purpose described, consisting of the combination of a drum having its longitudinal axis protruding from each end and mounted upon grooved wheels

adapted to travel upon suitable tracks in suitable manner to allow both a longitudinal and revolving movement of said drum, in combination with a grinding-wheel belted 5 to a suitable power medium and suspended over said drum by means of protruding hinged arms having their unconfined or swinging ends connected by a cross-piece and suspended by a spring in such manner that the said grinding-wheel may be made to come in contact 10 with the surface of the said drum at the will

of the operator, substantially in the manner shown, and for the purpose set forth and described.

In testimony whereof I have hereunto subscribed my name, in the presence of two witnesses, this 23d day of March, A. D. 1889.

THAXTER SHAW.
